(57) **CLAIM**

The ornamental design for an electric folding bed as shown and described.

DESCRIPTION

FIG. 1 is a top, front, right side perspective view of an electric folding bed, showing my new design in a first configuration of use;

FIG. 2 is a bottom, rear, left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a right side view showing the electric bed in a second configuration of use;

FIG. 10 is a right side view showing the electric bed in a third configuration of use;

FIG. 11 is an enlarged view of portion 11 shown in FIG. 1; and,

FIG. 12 is an enlarged view of portion 12 shown in FIG. 2. The dash-dash broken lines in the drawings depict portions of the electric folding bed that form no part of the claimed design.

The dot-dash broken lines represent boundaries of the enlarged portions and form no part of the claimed design.

1 Claim, 12 Drawing Sheets
